SAFETY RAZOR

Harry B. Carter, Palestine, Tex.

Application August 22, 1945, Serial No. 611,951

1 Claim. (Cl. 30—57)

1

The present invention relates to new and useful improvements in safety razors and more particularly to a razor of the single-edge blade type, and the invention has for its primary object to provide means for easily and quickly mounting the blade in position on its guard and assembling the same together with the guard as a unit on the handle of the razor.

A further important object of the invention is to provide a safety razor including a blade and a guard therefor together with means for adjusting the blade on the guard when either attached to a handle or detached therefrom.

A still further object of the invention is to provide a device of this character of simple and practical construction, which is efficient and reliable in use, relatively inexpensive to manufacture and otherwise well adapted for the purposes for which the same is intended.

Other objects and advantages reside in the details of construction and operation, as more fully hereinafter described and claimed, reference being had to the accompanying drawings forming part hereof, wherein like numerals refer to like parts throughout, and in which:

Figure 1 is a side elevational view.

Figure 2 is a front elevational view.

Figure 3 is a vertical sectional view taken substantially on a line 3—3 of Figure 2.

Figure 4 is a top plan view of the guard.

Figure 5 is a fragmentary transverse sectional view taken substantially on a line 5—5 of Figure 1.

Figure 6 is a perspective view of the blade.

Figure 7 is a perspective view of the holder for the blade and guard.

Referring now to the drawings in detail, wherein for the purpose of illustration I have disclosed a preferred embodiment of the invention, the numeral 5 designates the handle of the razor to the upper end of which is secured a U-shaped extension 6 having a tongue 7 formed at its bight portion for securing to a shoulder 8 on the upper end of the handle to provide a rigid connection between the extension and the handle.

The legs of the extension 6 are of resilient material and extend upwardly in spaced-apart parallel relation, as indicated in Figure 2 of the drawings, and the upper ends of the legs of the extension are formed with openings 9 adapted to receive the trunnions 10 projecting outwardly at the opposite side edges of a blade 11, the blade being of a single-edge type and formed with a beading 12 at its rear edge.

The blade 11 is adapted to rest on a flat guard 13 having a slot 14 extending forwardly from its rear edge, the edges of the slot being countersunk, as indicated at 15.

5 The blade and guard are secured in assembled relation on a transversely extending U-shaped holder 16 having relatively short upstanding legs 17 at the ends thereof and having slots 18 in the rear edges of the legs and extending forwardly thereof, the slots being adapted to receive the trunnions 10 of the blade.

10 A retaining screw 19 is extended upwardly through an opening 20 in the holder 16, the screw having a square head 21 on its upper end adapted for seating on the countersunk portion 15 of the slot 14 to prevent turning of the screw, the head bearing against the under side of the blade 11, as will be apparent from an inspection of Figure 5 of the drawings. A wing nut 22 is 15 threaded on the lower end of the screw.

20 The blade 11 and guard 13, when assembled on the holder 16, may be secured on the upper end of the extension 6 for the handle by spreading the sides of the extension apart to receive 25 the trunnions 10 of the blade, to thus mount the blade, guard and holder between the sides of the extension, as illustrated in Figure 5 of the drawings.

20 One edge of the legs of the extension 6 are 30 formed with eyes 23 having an entrance slot 24 in the upper portion thereof and adapted for receiving a U-shaped brace 25 having its ends extending upwardly and forwardly and of resilient material and formed with openings 26 at 35 their upper ends for engaging pins 27 projecting outwardly at the sides of the guard 13 at the front end thereof.

30 The upper surface of the guard 13 at its front edge is also provided with an upstanding rib or 40 lug 28 bearing against the under side of the blade at its front edge to maintain the blade in spaced relation above the guard, as will be apparent from an inspection of Figure 3 of the drawings.

40 The holder 16 may be adjusted forwardly or 45 rearwardly with respect to the blade 11 and guard 13 by loosening the wing nut 22 and sliding the head 21 by the wing nut longitudinally in the slot 14, the slots 18 of the holder 16 providing for this adjustment on the trunnions 10 of the blade.

50 The pivotal connection of the brace 25 with the guard also provides for tilting of the guard 13 and blade 11 by such forward or rearward adjustment of the guard.

55 In view of the foregoing description taken in conjunction with the accompanying drawings, it

is believed that a clear understanding of the construction, operation and advantages of the device will be quite apparent to those skilled in the art. A more detailed description is accordingly deemed unnecessary.

It is to be understood, however, that even though I have herein shown and described a preferred embodiment of my invention, the same is susceptible to certain changes fully comprehended by the spirit of the invention as herein described and the scope of the appended claim.

Having thus described the invention, what I claim is:

A safety razor comprising a handle having laterally spaced end arms, a rectangular blade between said arms with a longitudinal cutting edge and end pins journaled in said arms whereby said blade is tilttable into different angular positions relative to said handle, a plate-like guard backing said blade with a front guard edge, said guard being tilttable to tilt said blade, a bar-like guard holder backing the guard, said holder having right angled ends straddling said blade and guard and slotted with said pins extending

through the slots whereby said holder is slidable forwardly and rearwardly of said guard and swingable on said pins to tilt the guard, a brace pivotally connected to said arms and to said guard to cause tilting of the guard upon sliding of said holder, a headed stud slidably extended through said holder for clamping said guard to the holder in different positions into which the holder is slid and the guard tilted, said guard having a transverse slot therein through which the headed end of the bolt extends whereby the holder is slidable relative to the guard, and a nut on the other end of said stud for tightening said stud to clamp the guard to the holder.

HARRY B. CARTER.
